(57) **CLAIM**

The ornamental design for a breech plug for disrupter unit, as shown.

DESCRIPTION

The invention described herein may be made or used by or for the U.S. Government for U.S. Government purposes.

FIG. 1 is a top plan view of the breech plug for disrupter unit; FIG. 2 is a right side elevation view of the breech plug for disrupter unit;

FIG. 3 is a front elevation view of the breech plug for disrupter unit;

FIG. 4 is a bottom plan view of the breech plug for disrupter unit;

FIG. 5 is a left side elevation view of the breech plug for disrupter unit;

FIG. 6 is a rear elevation view of the breech plug for disrupter unit; and,

FIG. 7 is an isometric view of the breech plug for disrupter unit.

Views are orthogonal projections unless otherwise noted. The various views are not necessarily to scale in order to better illustrate the design.
